LIQUID DISPENSING APPARATUS

Ivan R. Farnham, Fred W. Sturm, and Friedrich W. Mueller, Fort Wayne, Ind., assignors, by mesne assignments, to The Wayne Pump Company, Fort Wayne, Ind., a corporation of Maryland

Application April 15, 1933, Serial No. 666,372

17 Claims. (Cl. 221—95)

This invention pertains to a liquid dispensing apparatus, and more particularly to an interlocking mechanism for preventing further operation of the liquid dispensing apparatus after dispensing operation and until the counter thereof has been set back to zero.

The invention comprehends the idea of providing novel control means for controlling the operation of a power means for delivering fluid from dispensing apparatus. More particularly, the invention includes the providing of novel means associated with the indicating means provided in the apparatus which is adapted to render the power means initially inoperative except when the indicating means is in a predetermined position.

Another object of the present invention is to provide a novel control means for controlling the initial operation of a manually operated switch or other similar means for closing the circuit of an electric motor adapted to dispense fluid from a fluid dispensing apparatus, such control means being associated with an indicating means of the apparatus in such a manner as to render this switch initially operative only when the indicating means is in a predetermined position, such as a zero reading. This novel control means, therefore, has the distinct advantage of providing a means whereby operation of the fluid dispensing apparatus can be effected only after the attendant has moved the indicating means back to its initial or zero reading, thereby positively indicating to the individual receiving the fluid that the position of the indicating means at any time corresponds with the number of units of fluid actually dispensed from the apparatus.

Still another object is to provide a liquid dispensing apparatus having reset means for the indicating mechanism in association with control means whereby the power means is operative only after the registering means is reset to zero.

With these and various other objects in view, the invention may consist of certain novel features of construction and operation as will be more fully described and particularly pointed out in the specification, drawings and claims appended hereto.

In the drawings, which illustrate embodiments of the device and wherein like reference characters are used to designate like parts—

Figure 1 is a sectional elevation of a liquid dispensing apparatus embodying the invention;

Figure 2 is an enlarged sectional elevation of one form of interlocking mechanism embodying

the invention, the same being taken substantially in the plane as indicated by the line 2—2 of Figure 3;

Figure 3 is a side elevation of the interlocking mechanism, the same being taken in the position as shown in Figure 1, showing the mechanism in a position where the registering mechanism is set to zero and with the switch operating arm lowered whereby the switch is in off position;

Figure 4 is a sectional elevation corresponding to Figure 2 showing the switch and operating arm in on position, the same being taken substantially in the plane as indicated by the line 4—4 of Figure 5;

Figure 5 is a side elevation corresponding to Figure 3 showing the switch operating arm in raised position whereby the switch is operative;

Figure 6 is a side elevation corresponding to Figure 3 showing the switch operating arm in lowered position after it has been in the position illustrated in Figure 5;

Figure 7 is a sectional elevation corresponding to Figure 2, the same being taken substantially in the plane as indicated by the line 7—7 of Figure 6;

Figure 8 is a side elevation of a modified form of interlocking mechanism showing the same in the first position wherein the registering mechanism is in the zero position and before the switch operating arm has been raised to close the switch;

Figure 9 is a sectional side elevation taken substantially in the plane as indicated by the line 9—9 of Figure 8;

Figure 10 is a fragmentary sectional elevation taken substantially in the plane as indicated by the line 10—10 of Figure 9;

Figure 11 is a sectional side elevation corresponding to Figure 8 showing the switch operating arm in raised position to close the switch;

Figure 12 is a sectional elevation taken substantially in the plane as indicated by the line 12—12 of Figure 11;

Figure 13 is a sectional elevation taken substantially in the plane as indicated by the line 13—13 of Figure 12;

Figure 14 is a side elevation corresponding to Figure 8 showing the switch operating arm in lowered position after registering has taken place at the meter wherein the switch and the liquid dispensing apparatus are inoperative;

Figure 15 is a sectional elevation taken substantially in the plane as indicated by the line 15—15 of Figure 14;

Figure 16 is a sectional elevation taken substantially in the plane as indicated by the line 16—16 of Figure 15.

Referring first of all more particularly to Figure 1, the liquid dispensing apparatus consists essentially of the base 30 adapted to support the casing 32, the framing 34 secured to the base and within the casing being provided with the platforms 36 and 38, the platform 36 being adapted to support a pump 40 and the motor 42 which is operatively connected to said pump. The suction side of the pump is connected through the pipe 44 to the source of liquid supply 46, and upon operation is adapted to draw the liquid from the source of supply 46 and supply it to the inlet side of the meter 48 through the pipe 50. An expansion chamber 52 may be provided associated with the pump for taking care of any expansion in the liquid dispensing apparatus. The outlet side of the meter 48 is connected through the pipe 54 to the sight gauge 56 to which the hose 58 is connected, the end of the hose being provided with the nozzle valve 60 having the operating handle 62 and the guard 64 associated therewith.

The meter 48 is provided with the rotating shaft 66 controlled by suitable pistons provided in the meter, the shaft being connected to registering and computing mechanism 68 as illustrated in Patent No. 1,888,533. The registering mechanism is adapted to be reset by means of the shaft 70 controlled by the crank 72. The operation of the motor 42 is controlled by a suitable electric switch 74 interposed in the current conduit 76, the switch being controlled by the link 78 connected to the switch operating arm 80, said arm being pivoted as at 82 to the interlocking mechanism housing 84. The switch operating arm 80 is associated with the nozzle support 86 secured to the housing 84, the housing 84 being adapted to be secured to the framing 34 in the casing 32.

Referring now more particularly to the form of interlocking mechanism illustrated in Figures 4 to 7 inclusive, the switch operating arm 80 is loosely connected to the lever 88 pivoted to the housing bracket 90 as at 92, the opposite end of the lever 88 being loosely connected to the interlocking rod 94 through the block 96. The rod 94 is mounted for reciprocating movement in the track 98 provided in the housing 84, and the opposite end of the rod is adapted, in the zero position of the registering mechanism 68, to be received in a suitable aperture or cut out portion 100 provided in the member 102 of the reset shaft 104. The reset shaft 104 is journaled in the housing 84 as at 106, and as shown is provided with the gear 108 meshing with the gear 110 provided on the crank shaft 112, the crank shaft being journaled in the housing as at 114, the outer end of said shaft being provided with the reset crank 72.

The reset shaft is provided with the cam 118 adapted to engage the plunger 120 mounted for reciprocation in the housing 84 and urged upwardly toward the cam by means of the spring 122, the plunger being loosely connected to the leg 124 of the bell crank 126, said bell crank being pivotally mounted as at 128 to the housing 84, the depending leg 130 of the bell crank being loosely connected to the latch 132 slidably mounted in the channel or track 134. The inner end of the latch 132 is urged downwardly by means of the spring 136 provided in the housing 84 the inner end of the latch being notched as

at 138 to provide a latch member 140, the notched portion being adapted to embrace the upwardly extending latch arm 142 provided on the switch arm 80. The latch arm 142 is provided with oppositely facing latch ledges 144 and 146 adapted to have latching cooperation with the latch member 140 of the latch 132.

In operation of this form of the device, assuming the registering mechanism to be in zero position and the switch 74 to be in off position as shown in Figures 2 and 3, when it is desired to operate the liquid dispensing apparatus, the switch arm 80 is raised to the position as indicated in Figure 5 to close the switch 74. Movement of the switch arm 80 in a counterclockwise direction to raise said switch arm causes rotation of the lever 88 in a counter-clockwise direction as viewed in Figure 4 whereby the interlocking rod 94 is raised to cause the end of said rod to enter the aperture 100 of the member 102, thus preventing any tampering with the registering mechanism 68. The cam 118 will be out of engagement with the plunger 120 whereby the latch 132 will have been moved toward the right as viewed in Figure 4, the latch portion 140 riding up on the bevel of the latch ledge 144 whereby the arm 80 can be moved to full upward position to close the switch 74.

After dispensing the requisite amount as indicated by the registering mechanism 68, when it is desired to shut off the flow of liquid, the switch arm is depressed to the position as illustrated in Figures 6 and 7. Depressing the switch arm causes the lever 88 to move in a clockwise direction to lower the interlocking rod 94 out of engagement in the aperture 100. Lowering the rod 94 causes the latch member 140 to ride off the ledge 144 and engage behind said ledge 144 whereby the switch arm cannot be re-raised without resetting the registering mechanism 68. This is done by rotating the crank 72. Rotation of said crank causes rotation of the reset shaft 104.

Rotation of said shaft causes the cam 118 to depress the plunger 120 to cause the bell crank 126 to be rotated in a clockwise direction to move the latch member 132 toward the left as viewed in Figure 2. This will cause the latch member to ride up on the bevel of the latch ledge 144 and remain there by virtue of engagement with the latch face, until the registering mechanism has been reset to zero and the operator has removed the discharge hose 58 from the switch arm 80 for serving a customer, but the registering mechanism will not reach its zero position until the aperture 100 is aligned with the interlocking rod 94. Therefore the switch arm 80 cannot be raised to operate the switch until the aperture is in that position, at which time the operation just described takes place, raising of the arm 80 causing the latch member 140 to again ride up the bevel of latch 144.

Referring now more particularly to the form of interlocking mechanism shown in Figures 8 to 16, inclusive, the interlocking mechanism 65 housing 150 is adapted to be secured to the framing of the liquid dispensing apparatus in the casing as already described with respect to the housing 84, the nozzle support 86 being secured to the bracket 152 of said housing. The switch operating arm 154 is pivoted as at 156 within the housing 150 and has an inwardly extending arm 158 loosely connected to the link 78 for operation of the switch 74.

The switch operating arm is provided with the 75

cam 160, said cam being provided with the locking shoulder 162 extending substantially parallel to the axis of the shaft 164 forming the pivot 156 of the switch arm 154. The locking member 166 is loosely pivoted to the shaft 164, being retained between the cam 160 and a suitable washer 168 mounted on said shaft. The locking member 166 is provided with the upwardly extending locking portion 170 adapted to have cooperative relation with the locking shoulder 162 and the leg 172 of the locking lever 174. The locking lever 174 is pivoted to the casing as at 176, the other leg 178 of said lever being urged upwardly by means of the spring 180, fastened 10 to the casing, said leg being adapted to have operative engagement with the plunger 182, said plunger slidably extending upwardly through the casing.

The shaft 164 is provided with the crank 184 loosely connected at 186 to the interlocking rod 188 slidably mounted in the housing. The reset shaft 190 for the registering mechanism is suitably journalled as at 192 in the housing and provided with the reset knob 194, said shaft being provided with the cam 196 disposed in alignment with the plunger 182, and the shaft is also provided with the member 198 aligned with the interlocking rod 188 and provided with the apertured or cut out portion 200 for the reception of 30 one end of the interlocking rod 188.

In operation of this device, assuming that the registering mechanism is in the zero position and the parts in the positions as illustrated in Figures 8, 9 and 10, with the switch arm lowered, 35 when it is desired to start the motor the switch arm is raised, causing the link 78 to close the switch 74. Raising the switch arm 154 to the position as illustrated in Figure 11 causes the locking shoulder 162 to move in a counter-clockwise direction as viewed in Figures 10 and 13 to move the locking portion 170 out of engagement with the leg 172 of the lever 174, causing the lever 174 to drop down onto the cam 160.

After the liquid has been dispensed and it is desired to render the liquid dispensing apparatus 45 inoperative, the switch arm 154 is lowered to the position as illustrated in Figures 14, 15 and 16. Lowering the switch arm causes the leg 172 of the locking lever 174 to drop off the cam 160, it being noted that the cam is of less height than the locking portion 170 so that the long leg 172 of the lever will engage between the cam and the locking portion 170 as shown in Figure 16. It will therefore be impossible to raise the switch 50 arm 154 as the shaft 164 is locked so long as the registering mechanism has not been moved to the zero position.

Assuming that the discharge hose is hung up on the switch-arm 154, the turning of the reset knob 60 194 to reset the registering mechanism back to zero position causes cam 196 to push down on plunger 182, which contacts the leg 178 of the locking lever 174 and pushes it down far enough to force the other leg 172 of the locking lever up high enough to permit spring 202, which is interposed between the housing and the leg 204 provided on said locking portion, to move the locking portion 170 to a position below the leg 172, but the switch arm 154 cannot be moved to close the switch 74 until full zero position, when the cut out portion 200 of the member 198 will be in alignment with the interlocking rod 188, at which time upward movement of the switch arm causes the 75 interlocking rod to enter the cut out portion to

permit depressing the link 78 to close the switch to operate the dispensing apparatus.

It will thus be appreciated that with the interlocking mechanisms illustrated simple means is provided for preventing further operation of a liquid dispensing apparatus until such time as the registering mechanism has been set to zero position, and in the event that the switch arm has been raised and the motor started whether or not any liquid is dispensed and the switch is again pulled down to inoperative position, it is necessary to again reset the registering mechanism back to the predetermined or zero position before the switch arm may again be raised, and it is to be understood that we do not wish to be limited by the exact embodiments of the device shown, which are merely by way of illustration and not limitation, as various and other forms of the device will of course be apparent to those skilled in the art without departing from the spirit of the invention or the scope of the claims.

We claim:

1. In interlocking mechanism, the combination of a switch arm having oppositely arranged latching shoulders, a latch member having a portion 25 adapted to have cooperative engagement with said latching shoulders to prevent operation of said switch arm, a shaft, and connecting means between said shaft and latch member for rendering said latch member inoperative to permit operation of the switch arm when said shaft is in a predetermined position.

2. In interlocking mechanism, the combination of a switch arm having oppositely arranged latching shoulders, a latch member having a portion 35 adapted to have cooperative engagement with said latching shoulders to prevent operation of said switch arm, a shaft, connecting means between said shaft and latch member for rendering said latch member inoperative to permit operation of 40 the switch arm when said shaft is in a predetermined position, and means interposed between said latch and shaft for rendering said shaft inoperative when said switch arm is in operative position.

3. In interlocking mechanism, the combination of a switch arm having oppositely arranged latching shoulders, a latch member having a portion 50 adapted to have cooperative engagement with said latching shoulders to prevent operation of said switch arm, a shaft, connecting means between said shaft and latch member for rendering said latch member inoperative to permit operation of the switch arm when said shaft is in a predetermined position, and means interposed between 55 said switch arm and shaft for rendering said shaft inoperative in a predetermined position thereof.

4. In an interlocking mechanism, the combination of a switch arm, a reset shaft, interlocking means between said switch arm and reset shaft whereby when said switch arm is in operative position said reset shaft will be inoperative, latching means interposed between said shaft and switch arm adapted to be operative to render 60 said switch arm inoperative after pre-determined operation of said switch arm, and means interposed between said latching means and reset shaft for moving said latching means to inoperative position to permit operation of said switch arm 65 after pre-determined operation of said reset shaft.

5. In an interlocking mechanism, the combination of a switch arm, a reset shaft, interlocking means between said switch arm and reset shaft whereby when said switch arm is in operative 75

position said reset shaft will be inoperative, latching means interposed between said shaft and switch arm adapted to be operative to render said switch arm inoperative after pre-determined operation of said switch arm, means interposed between said latching means and reset shaft for moving said latching means to inoperative position to permit operation of said switch arm after pre-determined operation of said reset shaft, said means including a cam mounted on said reset shaft, a plunger adapted to be moved by said cam, and a bell crank interposed between said plunger and latching means.

6. In reset mechanism, the combination of a switch arm pivotally mounted on a shaft, a reset shaft, interlocking means interposed between said reset shaft and switch for rendering said reset shaft inoperative when said switch arm is moved to a pre-determined position, a locking member pivotally mounted on said shaft, means operative by said switch arm for moving said locking member, and a lever adapted to cooperate with said locking member whereby said switch arm is rendered inoperative.

7. In reset mechanism, the combination of a switch arm pivotally mounted on a shaft, a reset shaft, interlocking means interposed between said reset shaft and switch for rendering said reset shaft inoperative when said switch arm is moved to a predetermined position, a locking member pivotally mounted on said shaft, means operative by said switch arm for moving said locking member, a lever adapted to cooperate with said locking member whereby said switch arm is rendered inoperative, and means cooperating with said lever and reset shaft for moving said lever to inoperative position for permitting operation of said switch arm.

8. In interlocking mechanism, the combination of a shaft, a switch arm mounted on said shaft, a cam mounted on said switch arm, said cam having a locking shoulder, a locking member pivotally mounted on said shaft and adapted to engage said locking shoulder, a lever pivotally mounted adjacent said shaft and having a portion adapted to cooperate with said cam and shoulder whereby in a predetermined position said lever will prevent operation of said switch arm.

9. In interlocking mechanism, the combination of a shaft, a switch arm mounted on said shaft, a cam mounted on said switch arm, said cam having a locking shoulder, a locking member pivotally mounted on said shaft and adapted to engage said locking shoulder, a lever pivotally mounted adjacent said shaft and having a portion adapted to cooperate with said cam and shoulder whereby in a pre-determined position said lever will prevent operation of said switch arm, a reset shaft, and means interposed between said lever and reset shaft for rendering said lever inoperative.

10. In interlocking mechanism, the combination of a shaft, a switch arm mounted on said shaft, a cam mounted on said switch arm, said cam having a locking shoulder thereon, a locking member pivotally mounted on said shaft and adapted to engage said locking shoulder, said locking member having a portion raised above said shaft, a lever pivotally mounted adjacent said shaft and having a portion adapted to cooperate with said cam and shoulder and adapted to be moved to engage a portion of said cam to prevent operation of said switch arm when said locking member is out of engagement with said locking shoulder.

75 11. In interlocking mechanism, the combina-

tion of a shaft, a switch arm mounted on said shaft, a cam mounted on said switch arm, said cam having a locking shoulder thereon, a locking member pivotally mounted on said shaft and adapted to engage said locking shoulder, said locking member having a portion raised above said shaft, a lever pivotally mounted adjacent said shaft and having a portion adapted to cooperate with said cam and shoulder and adapted to be moved to engage a portion of said cam to prevent operation of said switch arm when said locking member is out of engagement with said locking shoulder, and means for moving said locking lever out of engagement with said cam to permit engagement between said locking member and shoulder whereby said switch arm may be moved to operative position.

12. In interlocking mechanism, the combination of a shaft, a switch arm mounted on said shaft, a cam mounted on said switch arm, said cam having a locking shoulder thereon, a locking member pivotally mounted on said shaft and adapted to engage said locking shoulder, said locking member having a portion raised above said shaft, a lever pivotally mounted adjacent said shaft and having a portion adapted to cooperate with said cam and shoulder and adapted to be moved to engage a portion of said cam to prevent operation of said switch arm when said locking member is out of engagement with said locking shoulder, a reset shaft, and an interlocking means between said shaft and said reset shaft for preventing operation of the switch arm only when said reset shaft is in a pre-determined position.

13. In interlocking mechanism, the combination of a shaft, a switch arm mounted on said shaft, a cam mounted on said switch arm, said cam having a locking shoulder thereon, a locking member pivotally mounted on said shaft and adapted to engage said locking shoulder, said locking member having a portion raised above said shaft, a lever pivotally mounted adjacent said shaft and having a portion adapted to cooperate with said cam and shoulder and adapted to be moved to engage a portion of said cam to prevent operation of said switch arm when said locking member is out of engagement with said locking shoulder, means for moving said locking lever out of engagement with said cam to permit engagement between said locking member and shoulder whereby said switch arm may be moved to operative position, a reset shaft, and interlocking means between said shaft and said reset shaft for preventing operation of said switch arm only when said reset shaft is in a predetermined position.

14. In interlocking mechanism, the combination of a shaft, a switch arm mounted on said shaft, a cam mounted on said switch arm, said cam having a locking shoulder, a locking member pivotally mounted on said shaft and adapted to engage said locking shoulder, a member mounted adjacent said shaft and having a portion adapted to cooperate with said cam and shoulder whereby in a pre-determined position said member will prevent operation of said switch arm.

15. In interlocking mechanism, the combination of a shaft, a switch arm mounted on said shaft, a cam mounted on said switch arm, said cam having a locking shoulder, a locking member pivotally mounted on said shaft and adapted to engage said locking shoulder, a member mounted adjacent said shaft and having a portion adapted to cooperate with said cam and shoulder.

shoulder whereby in a pre-determined position said member will prevent operation of said switch arm, a reset shaft, and means interposed between said member and reset shaft for rendering said member inoperative.

16. In an interlocking mechanism, the combination of a switch arm, a reset shaft, interlocking means between said switch arm and reset shaft whereby when said switch arm is in operative position said reset shaft will be inoperative, 5 slideable latching means interposed between said reset shaft and switch arm adapted to be operative to render said switch arm inoperative after pre-determined operation of said switch arm, and 10 means interposed between said latching means and reset shaft for sliding said latching means to inoperative position to permit operation of said switch arm after the pre-determined operation of said reset shaft.

17. In an interlocking mechanism, the com- 15

bination of a switch arm, a reset shaft, interlocking means between said switch arm and reset shaft whereby when said switch arm is in operative position said reset shaft will be inoperative, slideable latching means interposed between said reset shaft and switch arm adapted to be operative to render said switch arm inoperative after pre-determined operation of said switch arm, means interposed between said latching means and reset shaft for sliding said latching 10 means to inoperative position to permit operation of said switch arm after the pre-determined operation of said reset shaft, said means including a cam mounted on said reset shaft, a plunger adapted to be moved by said cam, and a bell 15 crank interposed between said plunger and latching means.

IVAN R. FARNHAM.

FRED W. STURM.

FRIEDRICH W. MUELLER. 20
